UNITED STATES PATENT OFFICE.

ABE KRAMER, OF DES MOINES, IOWA.

DOUBLE SAFETY-ENVELOP.

1,285,238.

Specification of Letters Patent. Patented Nov. 19, 1918.

Application filed September 17, 1917, Serial No. 191,886. Renewed October 4, 1918. Serial No. 256,916.

To all whom it may concern:

Be it known that I, ABE KRAMER, a citizen of the United States, and resident of Des Moines, in the county of Polk and State 5 of Iowa, have invented a certain new and useful Double Safety-Envelop, of which the following is a specification.

The object of my invention is to provide an envelop, the inside of which may be used 10 for writing if desired, but which is particularly designed to afford safety against being opened during the transmission of mail.

More particularly it is my object to provide such an envelop, which can be folded 15 and sealed in such a way as to provide a first safety device, and a second safety device for absolutely preventing the opening of the envelop without leaving clear and conclusive evidence that the envelop has 20 been tampered with.

With these and other objects in view my invention consists in the construction, arrangement and combination of the various parts of the device, whereby the objects 25 contemplated are attained, as hereinafter more fully set forth, pointed out in my claims and illustrated in the accompanying drawings, in which:

Figure 1 shows a plan view of the blank 30 form which my envelop is formed.

Fig. 2 shows a view of the back of the envelop partially closed and sealed.

Fig. 3 shows a similar view of the envelop completely sealed and using both the 35 first and second safety devices.

Fig. 4 shows a similar view with a slightly different way of closing and sealing the envelop, and

Fig. 5 shows a sectional view through the 40 envelop shown in Fig. 4 taken on the line 5-5 of said Fig. 4.

In the accompanying drawings, I have used the reference numeral 10 to indicate generally the ordinary front of an envelop 45 having the end wings 11, the lower flap 12 and the upper flap 13.

The lower flap is provided with a longitudinally arranged slit 14. In connection with the lower flap I provide an auxiliary 50 strip 15 slightly longer than the slit 14 and having secured to one edge a tongue 16 which may be slightly tapered, as shown in Fig. 1, and which has a gummed portion 17 on one side, as shown.

The end of the tongue 16, at the point 55 of its juncture with the strip 15 is of such width to slip through the slit 14.

At the ends of the strip 15 are short tongues 18, designed to overlap the lower flap 12 adjacent to the ends of the slit 14. 60

Mucilage or gum or the like 19 is provided on the surface of the strip 15. The flap 13 is provided with a central tongue 20 and is also provided with a slit 21 having its central portion U-shaped, as at 21^a, as 65 shown in Fig. 1.

The edge of the flap 13 is gummed at 22.

In the practical use of my improved safety envelop, the end wings 11 are folded over, as 70 shown in Figs. 2, 3 and 4. The flap 12 is then folded over, as shown in Fig. 2, along the line 23. The top flap 13 is then folded over along the line 24 and the tongue 20 is moistened and slipped through the slot 14 in the interior of the envelop where it will 75 adhere to the gummed surface 19 of the strip 15, thereby forming a first safety device, so arranged that the envelop cannot be opened without showing that it has been tampered 80 with.

It will be seen that the strip 15 and the slot 21 may be dispensed with and the tongue 20 may be made to coat with the slot 14 to 85 form a safety device. When the device is so used the tongue 20 is inserted through the slot 14. When the envelop is closed, a gum may be provided either on the flap 12 or the under side of tongue 20, which may be moistened to seal the tongue in place. When this construction is used the sticking gum 90 will have two thicknesses of paper on either side of it, so that it will be almost impossible to steam the envelop whereby the gum on the tongue 20 may be loosened.

In order, however, to afford even greater 95 security, I have provided a second safety device. The tongue 16 can be simply folded down against the outer side of the flap 13 and secured thereto by moistening the gummed surface 17 leaving the envelop in the 100 condition shown in Fig. 4; or the tongue 25, formed by the portion 21^a of the slit 21, may be slightly raised and the tongue 16 inserted through the slit 21, after having its gummed surface moistened, for thereby fastening the 105 parts together and affording a second safety means. In this connection it may be mentioned that the surface of the tongue 25 is

gummed at 26, so that said gummed surface 26 may be moistened for fastening the tongue 25 down to the tongue 16.

The outer surface of the tongue 16 is also 5 provided with gum or mucilage near its top at 29.

It will thus be seen that I have afforded a double safety device so that there is no possibility of tampering with the envelop or 10 opening it in any way without visible evidences of such tampering being disclosed.

It is my intention to cover by my claims any modified forms of structure or use of 15 mechanical equivalents which may be reasonably included within the scope of my claims.

I claim as my invention:

1. A safety envelop comprising a front, 20 end wings folded over said front portion, a lower flap having a longitudinal slit adjacent to its free edge, an auxiliary strip of greater length than said slit and having a tongue extended therefrom through the slit away from said flap, said strip and tongue 25 both having their surfaces adjacent to said flap gummed, and an upper flap having a longitudinal slit therein adjacent to its free

edge of greater length than the width of said tongue, said upper flap having a tongue projecting from the free edge thereof and having its edges adjacent to the tongue gummed. 30

2. A safety envelop comprising a front, end wings folded over said front portion, a lower flap having a longitudinal slit adjacent to its free edge, an auxiliary strip of 35 greater length than said slit and having a tongue extended therefrom through the slit away from said flap, said strip and tongue both having their surfaces adjacent to said flap gummed, an upper flap having a longitudinal slit therein adjacent to its free edge comprising straight end portions and a U-shaped central portion whereby a tab may be formed, which may be grasped to pull apart 40 the two edges of the slit to more readily permit the entrance of the tongue, and a second tongue of less width than the length of the first described slit whereby said last described tongue may be inserted through 45 said first described slit between the lower flap and said auxiliary strip. 50

Des Moines, Iowa, September 13, 1917.

ABE KRAMER.
